UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CASING FOR LAMP-SOCKETS AND THE LIKE.

1,228,028.

Specification of Letters Patent.

Patented May 29, 1917.

Application filed December 18, 1913. Serial No. 807,455.

To all whom it may concern:

Be it known that I, CHARLES J. KLEIN, a citizen of the United States, residing at Milwaukee, in the county of Milwaukee, 5 State of Wisconsin, have invented new and useful Improvements in Casings for Lamp-Sockets and the like, of which the following is a full, clear, concise, and exact description, reference being had to the accompanying drawing, forming a part of this specification.

This invention relates to improvements in casings for pendent switches, lamp sockets or the like, and more particularly to interlocking means for the sections of such casings.

One of the objects of the invention is to provide improved interlocking means for the sections of such casings adapted to effect a composite longitudinal and transverse lock in both directions.

Other objects will appear hereinafter.

In order that my invention may be more clearly understood, I have illustrated the 25 preferred embodiment thereof in the accompanying drawing. It is to be understood, however, that the drawing is in certain respects merely exemplary of my invention and that the form shown is susceptible to 30 modifications without departing from the scope of the appended claims.

Figure 1 is a side view of a pendent switch casing of the feed-through type;

Fig. 2 is a similar view of the parts of the 35 casing shell when separated;

Fig. 3 is a side view of a lamp socket casing;

Fig. 4 is an enlarged side view of a portion of the casing having one set of interlocking means;

Fig. 5 is a perspective view of the same at an angle; and,

Fig. 6 is a central longitudinal section of the same when the parts are interlocked.

45 The casing shown in Fig. 1 comprises a cylindrical shell 1 and one or more caps 2 therefor. The shell is designed to house a switch having one or more reciprocating operating members 3. In order to facilitate 50 insertion of the switch, the shell is longitudinally divided on opposite sides and provided with apertures 4, at right angles to the line of division, to receive the switch operating members.

55 The interlocking means are employed for

securing the parts of the shell together and for holding the caps in releasable union with the ends of the shell. This means comprises a plurality of catches 5 and an equal number of shoulders 6 carried by the parts. 60 In the preferred form, the interlocking means for the cap and shell is identical with that for the parts of the shell. A description of the former will, consequently, suffice 65 for both.

Two catches 5 are provided on opposite sides of the caps, either at or adjacent its edge. These catches, in the preferred form, are similar to those described and claimed in my co-pending application, filed Oct. 28, 70 1913, Serial No. 797,871. Briefly described, each catch comprises a substantially triangular portion of the cap rim displaced inwardly and having a hooked upper wall 7 and converging side walls 8. The free edges 75 of the side walls are inherently beveled from the tip of each catch to the margin of the cap.

A pair of shoulders 6 are provided on opposite sides of the shell. In practice, each of these shoulders comprises an arc-shaped or reniform aperture 9 providing an upper bearing wall 6 and a tongue 10 constituting a lower bearing wall. This tongue is preferably inclined outwardly at a slight angle 80 to the body of the shell wall. As illustrated, the bearing surface 6 and the bearing surface of the tongue 10 are curvilinear in shape and form substantially concentric shoulders. 85

Attachment of the parts is readily accomplished by turning the assembled shell to align the apertures 9 with the catches 5 of the cap, whereupon the parts may be telescoped together. If desired, guide notches 90 11 may be cut in the edge of the shell above the apertures to facilitate initial alignment of the interlocking means. Due to the beveled conformation of the catches 5, attachment of the cap and shell is automatic, and, 95 due to the resiliency of the shell, engagement of the interlocking means is accomplished with a snap action. When the cooperating shoulders are thus interlocked the upper bearing surface of the catch wall 7 100 engages the upper bearing surface of the aperture wall 6 to lock the cap and shell against axial separation. At the same time the side walls 8 of the catch abut the depending bearing walls of the aperture to 105 110

lock the parts against relative rotation. Moreover, the bearing surface of each aperture wall 10 abuts the lower surface of the catch wall 7, as shown in Fig. 6, and thus 5 provides a positive stop against further overlapping of the parts. The depending sides of the tongues 10 likewise engage the lower depending surfaces of the side walls 8 of the catch to additionally lock the cap 10 and shell against relative rotation. The axial lock above described is rendered exceedingly effective, by reason of the inclination of the bearing surface 7 of the catch, since, as will be evident, any separative 15 strain on the parts of the casing tends to force the bearing surface 6 of the shell away from the free extremity of the catch. Furthermore, the effectiveness of the telescoping-limit lock is enhanced by reason of the outward inclination of the tongue 10, since the lower face of the catch wall 7 thus lies at right angles to the tongues 10, and any thrust exerted on the parts is taken up in a straight line engagement.

20 Separation of the cap and shell is readily obtained by compression of the latter beneath one or both of the apertures 9 until the same are freed from the corresponding catches, whereupon the shell may be withdrawn axially from the cap.

The parts of the shell are designed to overlap along their longitudinal edges and interlocking means, similar to that already described, is provided on the overlapping 35 edges of the shell to releasably lock the same together.

Fig. 3 shows a lamp socket casing comprising a cap and shell of the conventional type. The interlocking means above described are employed in this casing to hold the cap and shell together. The operation of this interlocking means is analogous to, and may be readily understood by, the description of the same as applied to the 45 pendent switch casing of Fig. 1.

An additional advantage of the structure of the interlocking means is that when the same are in engagement the apertures 9 are

completely filled, so that the casing is practically dust-tight as well as of a more ornamental appearance.

What I claim as new and desire to secure by Letters Patent is:

1. A casing for electric devices comprising in combination, telescoping sections and interlocking means therefor including an inwardly and upwardly bent catch on one section, upper and lower shoulders on the other section for engagement by said catch, the lower shoulder being offset to abut the under side of said upturned catch substantially at right angles to limit the telescoping of said sections.

2. A casing for electrical devices comprising in combination, separable sections having overlapping edges, a hooked and upwardly rounded catch on the outer section, substantially concentric arc-shaped shoulders on the inner section, the upper rounded surface of the catch engaging the upper shoulder for preventing axial separation of the sections, the lower shoulder being sprung outward to abut the hooked underside of the catch substantially at right angles to prevent telescoping of the sections, and the rounded sides of the catch engaging the shoulders for preventing relative rotation of the sections.

3. A casing for electrical devices, comprising in combination, separable overlapping sections, and marginal interlocking means therefor including an inturned and upturned catch on the outer section having rounded upper and lower bearing surfaces, and upper and lower arc-shaped shoulders formed in the inner section for engagement with said catch, the lower shoulder being offset to abut at right angles the lower bearing surface of said catch.

In witness whereof, I have hereunto subscribed my name in the presence of two witnesses.

CHARLES J. KLEIN.
